UNITED STATES PATENT OFFICE.

FRED D. HOLDSWORTH, OF CLAREMONT, NEW HAMPSHIRE, ASSIGNOR TO SULLIVAN MACHINERY CORPORATION, A CORPORATION OF MASSACHUSETTS.

COMPRESSOR-CONTROLLING MECHANISM.

1,363,204.

Specification of Letters Patent. Patented Dec. 21, 1920.

Application filed March 30, 1918. Serial No. 225,751.

To all whom it may concern:

Be it known that I, FRED D. HOLDSWORTH, a citizen of the United States, residing at Claremont, in the county of Sullivan and State of New Hampshire, have invented certain new and useful Improvements in Compressor-Controlling Mechanisms, of which the following is a full, clear, and exact specification.

10 My invention relates to compressor controlling mechanisms.

It has for its object to provide improved mechanism whereby a compressor may be controlled in an improved manner, the same, 15 while not necessarily limited thereto, being especially adapted to use in starting. A further object of my invention is to provide an improved controlling mechanism for unloading a motor driven compressor, whereby 20 through improved means the line pressure may be utilized at any time to unload the compressor, and especially to unload the same during starting in such a manner as to reduce the load upon the compressor driv- 25 ing motor during the starting of the latter. These and other objects and advantages of my improved construction will, however, hereinafter more fully appear.

In the accompanying drawings I have 30 shown for purposes of illustration one embodiment which my invention may assume in practice.

In these drawings,—

Figure 1 is a side elevation of a com- 35 pressor equipped with my improvement, certain portions of the same being broken away to facilitate illustration.

Fig. 2 is a detail side elevation of the controlling mechanism and its connections.

40 Fig. 3 is a detail vertical sectional view of a portion of this controlling mechanism, the pipe connections being removed.

In this illustrative construction I have 45 shown a compressor 1, which may be of any suitable type, but preferably, as herein, is provided with a piston 2 reciprocable in a suitable cylinder 3 which, in turn, is equipped with inlet valves 4, herein shown to be of the suction type, and discharge valves 5, so that 50 the piston may draw in air through the com-

pressor intake 6 and the inlet valves 4 and discharge the same in a well known manner through the discharge valves 5 into a discharge pipe 7 leading to a receiver 8.

Cooperating with the inlet valves 4, I have 55 herein shown pistons or plungers 9 carried in suitable cylinders 10 disposed beneath the valves 4 and adapted to be moved into engagement with the stems of the latter to raise the same from their seats against the 60 pressure of their seating springs 11 when pressure from a suitable source, as for instance the receiver, is supplied to these plungers through suitable pipe connections 12. As shown, pressure is herein supplied to 65 these pipe connections 12 through another suitable pipe connection 13, and the flow of fluid through the latter is controlled by a suitable controlling valve mechanism, herein indicated at 14. This valve mechanism may 70 assume various forms, but the same is illustrated herein as of the type which functions automatically, whenever the receiver pressure exceeds or drops below a predetermined limit, to supply or exhaust receiver pressure 75 beneath the pistons or plungers 9 and thereby either elevate the latter and the suction valves to unload the compressor, or, by reducing the pressure beneath the plungers, 80 permit the springs 11 to seat the valves and load the compressor.

In this illustrative form of my invention, it will be observed that in Fig. 3 I have shown the valve mechanism 14 to be of a well known construction of the type includ- 85 ing a suitable casing having a diaphragm 15 therein and chambers 16 and 17 on its opposite sides. As shown, one of these chambers, i. e. the upper chamber 16, carries therein a suitable diaphragm engaging plun- 90 ger 18 which is acted upon by a spring 19, adjustable by means of an adjustable cap 20, which, in turn, preferably is provided with a port 21 opening to the atmosphere. As illustrated, the lower chamber 17 communi- 95 cates with the receiver 8 through the pipe connection 13, and carries therein a second diaphragm engaging plunger 22 acted upon by a suitable spring 23 and having a laterally branched longitudinal port 24 leading 100

down into a lower chamber 25 and controlled by a disk valve 26, which in turn is normally held elevated by a spring 27 and is provided with ports 28 and is adapted to control the 5 communication of the chamber 25 with the exhaust ports 29, or, when the plunger 22 moves upward, to conduct air through the ports 28 to the chamber 25, and so to a port 30 in the lower end of the chamber 25, while 10 closing off the exhaust ports.

In my improved construction, it will be noted that I have provided a bypass around the valve 14, the same being provided herein by operatively connecting a three-way pipe 15 section 31 with the lower end of a plug 32 housing the chamber 25, and connecting another three-way pipe connection 33 to a pipe 34 leading from the chamber 17, and then connecting the two pipe sections by suitable 20 means, as, for instance, an elbow pipe connection 35. Attention is also directed to the fact that I have provided suitable valve mechanism adapted to divert the pressure through the valve 14 or through the bypass, 25 as desired. Herein, it will be noted that I have shown a three-way valve 36 adapted to be controlled by a suitable manually adjustable controlling lever 37. Thus, it will be noted that the valve is adjustable at will 30 by the operator to establish communication between the receiver 8 and the pipe connections 12, either through the chamber 17, the passage 24, the valve 26, the port 30, and the valve 36; or through the pipe connections 35 33, 35, and the valve 36.

In the operation of my improved construction, it will be observed that the operator, whenever desired, during the starting, may utilize any existing pressure in the receiver 40 8 to lift the suction valves 4 from their seats and thereby unload the compressor. More specifically, it will be observed that by turning the valve controlling handle 37 so that the valve 36 causes the pressure fluid to 45 pass through the connection 35 in the bypass around the pilot valve 14, the fluid is supplied directly from the receiver to the inlet valves 4 to raise the latter from their seats and thus unload the compressor, so that the 50 motor driving the same is not subjected to a heavy load in starting. Obviously, after the motor has, however, reached its running speed, it will be evident that the operator, by simply moving the controlling handle 37 55 to its opposite position, *i. e.*, through 90° in a clockwise direction, may eliminate the bypass and cause the pressure from the receiver to pass through the pilot valve 14 in the usual manner, the compressor thereafter being automatically controlled by the valve 60 mechanism 14 in accordance with the variations in pressure in the receiver.

By the use of my improvement, it will be observed that it is possible to equip a compressor provided with the usual automatic

pressure controlled loading and unloading mechanism, with improved means whereby the same may be unloaded at will by fluid pressure either during starting or at any desired time, when the receiver pressure is 70 above a predetermined, relatively low limit. It will also be evident that the mechanism will in no way interfere with the normal automatic pressure control mechanism ordinarily provided, and that the same is exceedingly simple and adapted to be applied to the compressor at small expense. These and other advantages of my improved construction will, however, be clearly apparent to those skilled in the art. 75

While I have in this application specifically described one embodiment which my invention may assume in practice, it will be understood that this form of the same is used only for purposes of illustration, and that the invention may be modified and embodied in various other forms without departing from its spirit or the scope of the appended claims. 80

What I claim as new and desire to secure 90 by Letters Patent is:

1. In combination, a receiver, a compressor, fluid pressure actuated unloading means for said compressor, a branched connection between said receiver and said unloading means, automatic receiver pressure governed control means for said unloading means in one of said branches, and a three-way valve located at one of the branch points of the connection between the receiver and 100 the compressor unloading means. 95

2. In combination, a receiver, a compressor, fluid pressure actuated unloading means for said compressor, a connection between said receiver and said unloading means, 105 automatic receiver pressure governed control means for said unloading means located in said connection, a shunt connection around said control means and a three-way valve arranged at the junction of said connections 110 adjacent the unloading means.

3. In combination, a receiver, a compressor, fluid pressure actuated unloading means for said compressor, a connection between said receiver and said unloading means, a receiver pressure governed control means for said unloading means located in said connection, a shunt connection around said control means, and a three-way valve located at the junction of said connections 115 120 adjacent the unloading means, and operative when in its opposite positions to open one of said connections and close the other thereof adjacent its outlet end.

4. In combination with a receiver, a compressor having suction operated unloading valves, a fluid pressure controlled unloading means therefor comprising automatic means having connections with said receiver and said unloading means and controlled by re- 125 130

ceiver pressure, said automatic means being operative to supply pressure from said receiver to said unloading means and to exhaust pressure from the latter, a shunt connection around said automatic means, and manually controlled means located at the point of junction of said shunt connection

with the connection between said automatic means and said unloading means, said manually controlled means being operative to 10 open one of said connections while closing the other.

In testimony whereof I affix my signature.
FRED D. HOLDSWORTH.
